(57) **CLAIM**

I claim the ornamental design for an electronic device holder, as shown and described.

DESCRIPTION

FIG. 1 is a perspective view of an electronic device holder receiving an electronic device;

FIG. 2 is a perspective view of an electronic device holder;

FIG. 3 is a left side view of an electronic device holder;

FIG. 4 is a right side view of an electronic device holder;

FIG. 5 is a front view of an electronic device holder;

FIG. 6 is a rear view of an electronic device holder;

FIG. 7 is a top view of an electronic device holder; and,

FIG. 8 is a bottom view of an electronic device holder.

The portions shown in broken lines form no part of the claimed design.
